WINDOW FIXTURE

George W. Hartman, Holland, Mich.

Application May 26, 1943, Serial No. 488,601

1. Claim. (Cl. 248—262)

The present invention relates to new and useful improvements in window fixtures, and has for its primary object to provide, in a manner as hereinafter set forth, a combination device of this character comprising a novel construction and arrangement for supporting curtains, shades, and drapes.

Another very important object of the invention is to provide a combination fixture of the aforementioned character which may be expeditiously and firmly mounted in position on the upper corner portions of the trim of a window frame without the necessity of driving thereinto nails, screws, or other extraneous securing elements.

Other objects of the invention are to provide a combination curtain, shade, and drape fixture of the character described which will be relatively simple in construction, strong, durable, highly efficient and reliable in use, inconspicuous, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation, showing a pair of fixtures constructed in accordance with the present invention mounted in position on a window.

Figure 2 is a top plan view thereof.

Figure 3 is a vertical sectional view, taken substantially on the line 3—3 of Figure 1.

Figure 4 is a perspective view of the hanger.

Figure 5 is a perspective view of the inner jaw which is mounted on the lower end of the hanger.

Figure 6 is a perspective view of the drape bracket which is mounted on the hanger.

Figure 7 is a view in front elevation, showing an intermediate fixture to be used on double windows.

Figure 8 is a view in front elevation of a slightly modified hanger.

Figure 9 is a view in side elevation of the modified hanger.

Referring now to the drawings in detail, it will be seen that reference numeral 1 designates generally a hanger which is adapted to be suspended from the head trim 2 of a conventional window 3 at an upper corner portion of said window. The hanger 1 includes a vertical bar 4 of suitable sheet metal which terminates at its upper end in a hook 5 which is engageable with the upper edge of the head trim 2. At its lower end the

bar 4 terminates in a forwardly directed transverse eye 6.

Mounted on the ends of the tubular eye 6 are laterally projecting arms 7 and 8. The arms 7 and 8 include, on their inner ends, forwardly directed apertured ears 9 which are secured by a bolt 10 to the eye 6. At its outer end, the arm 7 terminates in a rearwardly directed jaw 11. The arm 8 is provided on its free end with an integral jaw 12. The jaws 11 and 12 grip therebetween the vertical trim of the window 3. The jaw 12 includes, on its upper edge, a flange 14 which is engageable beneath the upper portion of the window frame. An angular bracket 15 is formed integrally with the lower edge of the jaw 12. The bracket 15 has formed therein a suitable opening or slot 16 for receiving the usual pintle on one end of a shade roller.

Projecting laterally from the bar 4 at an intermediate point and integral therewith is a bracket 17. The bracket 17 includes vertically aligned, slotted ears 18. The bracket 17 is adapted to support a removable drape bracket 19. The drape bracket 19 is substantially U-shaped and the legs 20 thereof are provided, on their free ends, with integral down-turned hooks 21 which are engageable in the slots 22 in the ears 18. Adjacent the bight portion of the bracket 19, the legs 20 thereof are further provided with openings 24, which openings are vertically aligned for the reception of a conventional drape rod.

It is thought that the manner of using the device will be readily apparent from a consideration of the foregoing. Briefly, one of the assemblies is secured in position on each of the upper corner portions of the window. This is accomplished by engaging the hook 5 over the upper edge of the trim and then drawing the jaws 11 and 12 together through the medium of the nut 25 on the bolt 10 for clamping the vertical trim therebetween. The opposed brackets 15 of a pair of the fixtures receive and support within the window frame a conventional shade roller 26, as shown in dotted lines in Figure 1 of the drawings. Forwardly projecting, upturned hooks 27 are formed integrally with the outer edges of the bars 4 immediately above the points at which the brackets 17 join said bars. The hooks 27 are engageable in the end portions of a conventional curtain rod for mounting same on the hangers 1. Then, as hereinbefore stated, if drapes are to be used, the brackets 19 are mounted on the brackets 17 and the usual rods are engaged in the vertically aligned openings 24.

In Figure 7 of the drawings, an intermediate

fixture 28 for double windows is illustrated. The fixture 28 includes a hanger 29 which is substantially similar to the hanger 1 with the exception that the drape bracket 17 is omitted and two curtain hooks 30 are provided, one on each of the vertical edges of said hanger 29. Then, in lieu of the elements 7 and 11, two of the arms 8 with the jaws 12, etc., thereon, are secured on the lower end portion of the hanger 29 for clamping therebetween the intermediate vertical trim 31 of the window frame. When the fixture 28 is used, said fixture is bridged by the curtain rod.

In the slight modification illustrated in Figures 8 and 9 of the drawings, the upper portion of the bar 4 of the hanger 1 extends forwardly at an angle of approximately 45 degrees, as at 32, and terminates in a reversely directed hook 33 for engagement over the head trim of the window. The portion 32 of the hanger is to accommodate trim which comprises forwardly protruding portions. In other respects this embodiment is substantially similar in construction to that illustrated in Figure 4 of the drawings.

All of the surfaces which would otherwise con-

tact the woodwork of the window are provided with a protective cover 34 of suitable material.

It is believed that the many advantages of a combination window fixture constructed in accordance with the present invention will be readily understood and although preferred embodiments of the device are as illustrated and described, it is to be understood that further modifications and changes in the details of construction 10 may be resorted to which will fall within the scope of the invention as claimed.

What is claimed is:

A window fixture comprising a hanger for mounting on the trim of a window, said hanger including a vertical bar, a hook on the upper end of the bar engageable over the trim, a bracket on the bar at an intermediate point including forwardly projecting, slotted ears, and a drape bracket removably mounted on the first named bracket, said drape bracket being substantially U-shaped and including down-turned hooks on the free ends of its legs engageable in the ears.

GEORGE W. HARTMAN.
